UNITED STATES PATENT OFFICE.

JOHN H. BRUNINGA, OF ST. LOUIS, MISSOURI, ASSIGNOR TO HESSE ENVELOPE & LITHO COMPANY, OF ST. LOUIS, MISSOURI, A CORPORATION OF MISSOURI.

ENVELOP-MAKING MACHINE.

1,259,354.

Specification of Letters Patent. Patented Mar. 12, 1918.

Application filed February 26, 1915. Serial No. 10,840.

To all whom it may concern:

Be it known that I, JOHN H. BRUNINGA, a citizen of the United States, and residing at St. Louis, in the State of Missouri, have invented a certain new and useful Improvement in Envelop-Making Machines, of which the following is a specification.

This invention relates to envelop making machines, and more particularly, to an attachment for such a machine, adapted to attach the transparency or panel to an address opening in the envelop face.

One of the objects of this invention is to construct mechanism which may be embodied in a machine as built, or applied as an attachment to an existing machine.

Another object is to provide mechanism which will accurately and positively position and apply a panel in correct relation with respect to the envelop blank and the opening therein, and which is capable of adjustment.

Another object is to provide mechanism whereby a continuous panel strip is fed to the machine, from the end of which strip a panel is cut and applied to the blank.

Another object is to provide pneumatic means for retaining the panel during its positioning movement, and for discharging the panel on the envelop blank.

Further objects will appear from the detail description taken in connection with the accompanying drawings, in which:

Figure 1 is a vertical section of the upper part of a well-known form of envelop machine, showing the attachment applied thereto;

Fig. 2 is an end elevation;

Fig. 3 is an enlarged detail right side elevation, showing the attachment;

Fig. 4 is an enlarged detail left side elevation;

Fig. 5 is a top plan view with the roll removed;

Fig. 6 is a diagrammatic view of the different cams and cam rolls;

Fig. 7 is a section on the line 7-7, Fig. 4; and,

Fig. 8 is a view of the envelop blank.

Referring to the accompanying draw-

ings, and more particularly, to Fig. 8, B designates an envelop blank having flaps C and D, a window or opening E, and a transparent panel or transparency F covering the opening E. This blank is of usual form, and is adapted to be creased and folded with any well known form of mechanism.

Referring now more particularly to Figs. 1 and 2, which show a well known form of envelop machine to which this invention is applied in the form of an attachment, 10 designates the base or frame, which is supported by suitable standards, and has mounted therebelow the main drive shaft and the cams operating the various parts of the machine. A bracket 11 has bearings for a vertically reciprocating shaft 12, which has mounted, at its lower end, the main pickers 13 and 14 for cementing the flaps C and D, and an auxiliary picker 15 for cementing the margin around the opening E. The pickers 13 and 14 are adjustably mounted on the lower end of the picker shaft 12 for adjustment longitudinally of the machine, and the auxiliary picker 15 is mounted for similar adjustment, whereby the pickers may be adjusted for different sized blanks. The cement is applied to the pickers by the usual cementing roll 16. The envelop blanks are carried by the pickers 13 against the slotted table 17, at which point they are carried forwardly by a conveyer 18 operated by a lever 19, upon the creasing table 21. This creasing table has a creasing box or die 27, and into this die extends a movable arm or support 20 for supporting the envelop blank at an intermediate line. A plunger 22 mounted on a shaft 23 reciprocating vertically in bearings in the yoke 24 is adapted to coöperate with the creasing die or box 27 to crease the blank. Folding mechanism comprising folders 25 and 26 fold the creased blank. The plunger is slotted or recessed, as shown at 28, for a purpose hereinafter to be described.

Mounted on the support 10 are a pair of standards 36 provided with laterally extending lugs 37 upon which are mounted a pair of brackets or end frames 39. A bracket 40 is also mounted on one of the

standards 36. A drive shaft 41 is mounted in the brackets 39 and 40, and this shaft has a sprocket 42 connected by a chain 43 with any suitable shaft on the machine, so as to operate the mechanism in timed relation with the other mechanism of the envelop machine. The brackets 39 are slotted, as shown at 45, to receive a shaft or mandrel 44 of the transparency or panel strip roll 46, whereby the roll may be removed and replaced at pleasure.

Shafts 47 and 48 are mounted in the brackets 39, and these shafts have mounted thereon suitable feeding rolls 49 and 50 connected by gears 51, so as to revolve together. The shaft 47 is mounted, at its ends, in blocks 52 movable in guides 53 and engaged by springs 54, each bearing, at one end, against the block, and at the other end, against an adjustable screw 55. The shaft 48 has mounted thereon a ratchet 56 engaged by a pawl 57 on a sleeve 58. This sleeve has formed thereon a gear 59 engaged by a rack 60 retained on the gear by a pair of side flanges on the gear, and a roll 61 mounted on the bracket 39. The rack is forked to embrace the drive shaft 41, and is provided with a cam roll 62 engaging a cam groove 63 in the cam disk or wheel 65, so that rotation of the drive shaft will intermittently rotate the rolls 49 and 50, each a half revolution. A collar 64 retains the sleeve 58 in position.

A stationary cutter 66 is mounted between a pair of lugs 67 on the brackets 39, and pivoted on one of the lugs at 68 is a movable cutter 69 cooperating with the stationary cutter. A lug 70 on the free end of the movable cutter is engaged by the slotted end 10 of the lever 71 pivoted intermediate its ends at 72 on one of the brackets 39, and having a cam roll 73 engaging a cam groove 74 in one face of a cam disk or wheel 75 fixed to the drive shaft 41. Mounted below the cutters is a projecting shelf 76 adapted to receive the panel as severed from the strip. Rotation of the drive shaft will cause the movable cutter to move toward and from the stationary cutter, and the pivotal connection between the blades is so relatively positioned, and the movement given to the free end is such as to cause the cutters to clear when open to permit the free end of the panel strip to be fed therethrough.

55 A rock shaft 77 is mounted in the brackets 39, and this rock shaft has fixed thereto a pair of arms 78 and 79. A link 80 connected to the arm 78 is forked to embrace the drive shaft 41, and is provided with a cam roll 81 engaging a cam groove 82 in the cam disk or wheel 75. The pivotal connection between the arm 78 and the link 80 is made by an eccentric 83, adjustably mounted on the connecting pin and clamped in ad-

justed position by means of a bolt 84. With 65 this construction, rotation of the drive shaft 41 will cause the rock shaft 77 to oscillate to move the arms from full to dotted position, Fig. 3. Adjustment of the eccentric 83 will adjust the position of the arms with 70 relation to the plunger. It will be noted that these arms enter the slots 28 in the plunger, so that the ends will move underneath the plunger when the latter is in raised 75 position.

A cylinder 85 is loosely mounted on the rock shaft 77, or bolted to one of the brackets 39, and this cylinder has a piston 86 provided with a piston rod 87 forked at its free end to embrace the drive shaft 41, and 80 provided with a cam roll 88 engaging a cam groove 89 in a cam disk or wheel 90 on the drive shaft 41. The cylinder, which is without valves, has a nipple 91 connected by flexible tubing 92 with the channels 93 in 85 the arms 78 and 79. The end faces 94 of the arms are each curved on the arc of a circle having the rock shaft 77 as a center. Rotation of the drive shaft will reciprocate the piston in the cylinder, and alternately 90 decrease and increase the pressure of the air in the cylinder and in the channels in the arms above and below atmospheric pressure.

The cam disks are adjustably mounted on the drive shaft, so as to permit adjustment 95 of the timed relation of the mechanisms operated thereby, and the relative positions of the cam grooves and the cam rolls are clearly shown in Fig. 6.

The operation of this machine is as follows:

Starting with the parts in the position shown in the drawings, as the shaft 41 revolves in the direction of the arrows, the cam groove 63 will operate, through its pawl 105 and ratchet connections with the shaft 48, to rotate this shaft through one-half of a revolution and feed the panel strip. At this time the cutter blade 69 has moved sufficiently away from the stationary cutter 66 110 to permit feeding of the strip between the cutters. The arms 78 and 79 are now moved to dotted position, Fig. 3, by their cam, so as to be over the strip on the table 76 at the time when this strip is fully fed. The piston 86 now moves outwardly in the cylinder and creates a partial vacuum in the recesses 93 of the arms 78 and 79, thereby 115 causing the panel strip to be drawn against the faces 94 of the arms. At this time, the cutter cam operates to move the movable cutter 69 downwardly to shear off the end of the panel strip now held by the arms 78 and 79. The arms now swing forwardly to full line position, so as to position the panel 120 over the window in the envelop blank, the panel being retained by atmospheric pressure 125 during its movement with the arms.

The cam now moves the piston 86 inwardly into the cylinder and increases the pressure of the air, so as to blow the panel on the envelop blank. The arms now swing back, 5 and the plunger moves down into the creasing box to crease the envelop, which is then folded in the usual way.

It will be noted that the panel is moved underneath the plunger, but not against its 10 lower face, but close to the blank, the clearance being very small. This action is especially permitted as the curved lower faces 15 of the arms curve the panel upwardly so that it will clear the creasing table, even though the clearance be very small. With this construction it is, therefore, possible to position the panel very accurately with respect to the blank, and this position can be adjusted by the eccentric 83. The machine 20 may, therefore, be adjusted to place the panel in any suitable position on the envelop. The panel is positively held by atmospheric pressure acting uniformly on its 25 surface, and is discharged pneumatically by the pressure of the air. This not only accurately positions the panel on the blank, but also acts to firmly attach it, so that it cannot shift during the creasing and folding operation performed by the plunger. It will be 30 understood that in an envelop machine which attaches a panel to an envelop, the plunger does not do any attaching, for the reason that this plunger performs merely a creasing operation and often stops one-fourth 35 of an inch from the folding table. The actual pressing of the panel on the envelop is performed by the flap folders. In this construction, however, the pneumatic means positively positions and positively applies 40 the panel to the blank. The invention is simple in construction, as well as positive in its action generally. It can be applied to any machine in the form of an attachment, and can also be embodied in a machine as 45 built. By providing the ratchet teeth, overthrow is prevented, so that the panel strip will be fed accurately.

It is obvious that various changes may be made in details of construction without departing from the spirit of this invention. 50 It is, therefore, to be understood that this invention is not to be limited to the specific construction shown and described.

Having thus described the invention, what 55 is claimed is:

1. In an envelop machine, the combination with envelop blank folding mechanism comprising a plunger, of means for feeding a panel strip, means for severing a panel 60 from said strip, means for carrying the severed panel underneath said plunger and above the blank, and means for holding the panel on said carrying means and for positively and forcibly discharging the panel 65 from said carrying means when in position 65 over the blank to place the panel directly on the blank.
2. In an envelop machine, the combination with envelop blank folding mechanism comprising a plunger, of means for feeding 70 a panel strip, means for severing a panel from said strip, and adjustable means for carrying the severed panel underneath said plunger, said means being adapted to adjustably deposit the panel directly on the 75 blank.
3. In an envelop machine, the combination with envelop blank folding mechanism comprising a plunger, of means for feeding a panel strip, means for severing a panel 80 from said strip, and means constructed to retain said panel pneumatically for carrying the severed panel underneath said plunger, said means being adapted to forcibly discharge the panel pneumatically at the 85 proper moment for depositing the same directly on the blank.
4. In an envelop machine, the combination with envelop blank folding mechanism comprising a plunger, of means for feeding 90 a panel strip, means for severing a panel from said strip, means for carrying the severed panel underneath said plunger and above the blank, and pneumatic means for positively and forcibly discharging the 95 panel from the carrying means directly onto the blank.
5. In an envelop machine, the combination with envelop blank folding mechanism comprising a plunger, of means for feeding 100 a panel strip, means for severing a panel from said strip, means for carrying the severed panel underneath said plunger and above the blank, and pneumatic means for retaining the panel on said carrier and for 105 forcibly discharging the same from said carrying means directly onto the blank.
6. In an envelop machine, the combination with envelop blank folding mechanism comprising a plunger, of panel supplying means, 110 and means constructed to retain and forcibly discharge a panel pneumatically, said means being adapted to carry a panel underneath said plunger, and to deposit the panel directly on the blank. 115
7. In an envelop machine, the combination with envelop blank supporting and folding mechanism, of panel supplying means, and means constructed to positively discharge a panel pneumatically, adapted to position a 120 panel over and deposit the same directly on the blank.
8. In an envelop machine, the combination with envelop blank supporting and folding mechanism, of panel supplying means, and means constructed to retain and forcibly discharge a panel pneumatically therefrom, 125 said last named means being adapted to posi-

tion a panel over and deposit the same directly on the blank.

9. In an envelop machine, the combination with envelop blank supporting and folding mechanism, of means for feeding a panel strip, means for severing a panel from said strip, and means constructed to retain and forcibly discharge said panel pneumatically therefrom, said last named means being adapted to carry and position the severed panel over and deposit the same directly on the blank.

10. In an envelop machine, the combination with envelop blank supporting and folding mechanism, of panel supplying means, means for carrying a panel to position over a blank, and pneumatic means cooperating with said carrying means, constructed to hold the panel, by suction, on the carrying means while being positioned by the latter and to thereafter forcibly discharge the panel, under the pneumatic pressure, from said carrying means directly onto the envelop blank.

11. In an envelop machine, the combination with envelop blank supporting and folding mechanism, of panel supplying means, means for carrying a panel to position over a blank, a pneumatic cylinder associated with said carrying means, and a piston operating in said cylinder to hold the panel by suction on said carrying means while being positioned and to forcibly discharge the positioned panel from said carrying means directly onto the envelop blank.

12. In an envelop machine, the combination with envelop blank supporting and folding mechanism, of panel supplying means, and means for conveying a panel from said supplying means to position the same over the blank, said conveying means being adapted to hold the panel warped during movement.

13. In an envelop machine, the combination with envelop blank supporting and folding mechanism, of panel supplying means, and means for conveying a panel from said supplying means to position the same over the blank, said conveying means being adapted to engage the panel at spaced points along its length and hold the same warped transversely during movement.

In testimony whereof I affix my signature in the presence of these two witnesses.

JOHN H. BRUNINGA.
